UNITED STATES PATENT OFFICE.

EVARISTE L. JEAN, OF FALL RIVER, MASSACHUSETTS.

GAS-STOVE ATTACHMENT.

Application filed March 19, 1927. Serial No. 176,743.

The present invention relates to improvements in gas stoves and has reference more particularly to an attachment for normally locking the gas cocks in a closed position so that gas will not be permitted to escape through any of the burners of the gas stove when said burners are not ignited.

Another important object of the invention is to provide an attachment for gas burners which is cooperatively associated with the gas cocks and the pilot light control valve whereby said locking means will be automatically released from engagement with the gas cocks when the pilot control valve is manually actuated, thereby permitting any or all of the gas cocks to be actuated simultaneously spreading the flame from the pilot light to each of the burners so as to light any or all of the burners through which the gas may be delivered.

Another important object of the invention is to provide a gas stove attachment of the above mentioned character, which is of such construction as to permit the same to be readily and easily installed without necessitating any material alterations of the parts of the gas stove with which the attachment is associated.

A further object is to provide a gas stove attachment of the above mentioned character which is simple in construction, strong and durable, and further well adapted for the purposes for which it is designed.

Other objects and advantages of the invention will become apparent during the course of the following detailed description.

In the accompanying drawings, forming a part of this application, and in which like reference characters designate like parts throughout the views:

Figure 1 is a top plan view of the attachment embodying my invention showing the same installed on a gas stove.

Figure 2 is a sectional view taken approximately on the line 2-2 of Figure 1, looking in the direction of the arrows, for more clearly disclosing the connecting means between the pilot light control valve and the locking rod.

Figure 3 is a sectional view, taken approximately on the line 3-3 of Figure 1, looking in the direction of the arrows, and

Figure 4 is a detail perspective view of a portion of the locking rod.

In the drawings, wherein for the purpose of illustration is shown the preferred em-

bodiment of my invention, the numeral 1 designates the gas supply pipe which is supported at the front of the gas stove by the supporting brackets 2 in the usual manner. Extending rearwardly from the supply pipe 1 beneath the top 3 of the gas stove is the torch pipe or tube 4, the inner end of which is disposed upwardly as at 5 and provides a means for delivering gas to the pilot light designated generally by the numeral 6. As the construction of the pilot light forms no important part of the present invention, a detailed description thereof is thought unnecessary.

This pilot light extends through a suitable opening 7 provided therefor in the top 3 of the gas stove and is formed with the gas ducts or discharge openings 8, the same being disposed radially for projecting a flame to each of the burners 9 in the manner well known in the art.

A pilot light control valve 10 of the conventional construction is associated with the forward end of the pipe or tube 4 and this valve includes a button shaped head 11 mounted on the upper end of the vertically movable stem 12 whereby the same may be manually depressed for admitting a supply of gas from the main supply pipe 1 to the pilot light 6 in the manner also well known in the art.

In the present instance, I have illustrated four burners, although it is to be understood that the attachment embodying my invention can be equally well used with more or less burners. Gas is supplied to the respective burners by means of the pipes 13 which extend from the main supply pipe 1 and associated with each of these pipes 13 is the rotatable gas cock 14. The actuating handle of each gas cock is designated by the numeral 15 and extending laterally from the upper portion of the valve 16 of the gas cock is a pin 17, the purpose of which will be hereinafter more fully described.

My attachment comprises an elongated rod 18 which is journaled at its respective ends in the outermost supporting bracket 2 provided for the supply pipe 1. Extending rearwardly from the rod 18 and integrally associated therewith are the latches 19, the same being adapted for cooperation with the respective laterally extending pins 17, carried by the rotatable valves of the respective gas cocks in the manner as clearly shown in Figures 1 and 4 of the drawings. A nose

20 is formed on the outer end of each of these latch members and normally the pin 17 engages the shoulder formed at the juncture of the nose with the body portion of the 5 latch for locking the rotatable valve 16 of the gas cock 14 in a closed position.

The attachment further includes the provision of a pair of parallel spaced arms 21 which extend rearwardly from the intermediate portion of the shaft or rod 18 and are rigidly associated therewith. The outer ends of these arms are slotted as indicated at 22. These arms are disposed on opposite sides of the pilot light control valve 10 and 15 the control button 11 of the pilot light control valve is operatively connected to the arms 21 and the rod 18 in a manner to be now more fully described. A cap is provided on the vertically movable stem 12 and 20 this cap member is designated by the numeral 23. Depending from the sides of the cap member at diametrically opposite points are the fingers 24, the construction of which is more clearly disclosed in Figure 2. A pin 25 extends through the lower end of each finger and is operable within the respective slots 22 formed in the arms 21 whereby a pin and slot connection is provided between the inner ends of the arms and the lower ends of the 30 downwardly extending fingers.

Normally the parts are arranged as shown in the drawings and the several gas cocks are maintained in a closed position.

When any one of the gas burners 9 is to 35 be ignited, the cap member 23 which is disposed on top of the depressible head 11 of the pilot control valve is pushed downwardly, the pilot light valve will be open to admit a supply of gas from the main supply pipe 40 to the pilot light 6 and this additional supply of gas will eject a flame from the pilot light to each of the burners and simultaneously with the downward movement of the cap member 23, the shaft 18 will be rotated, due to the pin and slot connection between the fingers and arms. When the shaft 45 18 is rotated so as to move in a downward direction, the several latches 19 will move out of engagement with the laterally extending pins 17, thus permitting the rotary valves 16 of the respective gas cocks to be actuated whereby to turn on the gas and permit a supply of gas to be delivered to the burners. Any one or all of the gas cocks 50 55 may be opened when the shaft 18 is moved in the manner as above described.

As soon as the pressure is taken off of the cap member 23, the resilient means associated with the pilot light control valve will automatically return the parts to their initial

position, thus automatically moving the latches into engagement with the respective pins 17 and again locking the gas cocks which have not been opened in a closed position, thus preventing any possibility of 65 the cocks being accidentally turned on and causing gas to escape through the burners without being ignited.

The simplicity of my improved attachment enables the same to be readily and easily installed on a gas stove without necessitating any material alterations of the stove parts with which the attachment is to be associated, and furthermore, the device will, at all times, be positive and efficient in carrying out the purposes for which it is designed. 70

While I have shown the preferred embodiment of my invention, it is to be understood that various changes in the size, shape and arrangement of parts may be resorted to, 75 without departing from the spirit of the invention or the scope of the appended claims. 80

What I claim as new is:

1. In combination with a gas stove including the usual rotatable gas cocks and the 85 pilot light control valve, of a rod journaled for rotation adjacent the gas cocks, a pin projecting laterally from the rotatable valve of each gas cock, a series of latches carried by the rod and normally engaging the respective pins for locking the rotatable valves of the gas cocks in a closed position, and means operatively connecting the rod with the pilot light control valve whereby said rod may be actuated to disengage the latches 90 from the respective pins when the pilot light control valve is actuated to permit said gas cocks to be turned on, said aforementioned means comprising a cap member carried by the depressible member of the pilot light 100 control valve, a finger extending downwardly from said cap member, an arm extending laterally from said rod and operatively connected at its rear end to the lower end of said finger. 105

2. In combination with a gas stove including the usual rotatable gas cock, and the depressible pilot control valve, of a rod journaled for rotation adjacent the gas cock, a pin projecting laterally from the rotatable valve of the gas cock, a latch carried by the rod and normally engaging the pin for locking the rotatable valve of the gas cock in a closed position, and a link and lever connection between the depressible pilot control valve and said rod for disengaging the latch from engagement with the pin when the pilot light control valve is depressed. 110

In testimony whereof I affix my signature.

EVARISTE LOUIS JEAN.
